UNITED STATES PATENT OFFICE.

CHARLES W. BRENEMAN, OF CINCINNATI, OHIO.

SHADE-CLOTH WITH IDENTIFICATION-MARK THEREON.

No. 845,927.

Specification of Letters Patent.

Patented March 5, 1907.

Application filed June 11, 1906. Serial No. 321,191.

To all whom it may concern:

Be it known that I, CHARLES W. BRENEMAN, a citizen of the United States, residing at Cincinnati, in the county of Hamilton and State of Ohio, have invented certain new and useful Improvements in Shade-Cloths with Identification-Marks Thereon, of which the following is a specification.

My invention relates to improvements in shade-cloths with identification-marks thereon.

The marking must be such as not to injure the goods or to destroy the ornamental effect of the shade-cloth. Shade-cloth consists of 15 white or bleached muslin, the opposite sides of which are coated with a suitable coloring-matter. I have desired for some time to mark the shade-cloth with an identification, but was unable to find any way which did 20 not injure the goods or destroy the ornamental effect thereof until I devised the means herein set forth.

The features of the invention are set forth in the description of the accompanying drawings, forming a part of this specification, in which the figure represents a section of the shade-cloth A, having the identifying-mark "Brenlin" thereon, said name being an arbitrary identification. The letters constituting this identifying-name are pricked through

the shade-cloth near the margin. These minute orifices B, penetrating the shade-cloth, disclose at their edges the intermediate white of the muslin, so that the letters appear to be displayed through the coloring-matter in a series of white dots. The effect is ornamental, and the name is thus permanently imprinted on the shade-cloth without injury thereto.

I am aware that hat-bands and similar articles have been marked with identifying-names by forming the letters of a series of punches through the article, and I do not claim such a means broadly; but

What I claim is—

Shade-cloth consisting of white muslin the opposite sides of which are coated with coloring-matter, and an identifying-name formed of letters pricked through the shade-cloth disclosing the white edges of the intermediate uncolored muslin, whereby the identifying-name is displayed by letters formed of a series of white dots visible through the colored surface of the shade-cloth.

In testimony whereof I have hereunto set my hand.

CHARLES W. BRENEMAN.
